UNITED STATES PATENT OFFICE.

JAMES G. MACLAREN, OF MAMARONECK, NEW YORK, ASSIGNOR, BY MESNE ASSIGNMENTS, TO THE LAMSON COMPANY, A CORPORATION OF MASSACHUSETTS.

PRESSURE-CONTROLLING DEVICE FOR CONVEYER TUBES.

Application filed February 23, 1922. Serial No. 538,687.

This invention relates in general to pneumatic despatch apparatus and more particularly to means for automatically controlling the flow of air through the tubes in accordance with the work to be done.

The invention includes a controlling valve having directly connected operating means

- 10 when the tube is unoccupied by a carrier to permit only a relatively restricted flow of air through the tube but opening, upon the change in pressure conditions produced in the tube by the insertion of a carrier therein, 15 to permit an increased flow of air through the tube to bring about the propulsion of the carrier.

The invention also includes a balanced valve structure operable by slight changes 20 in pressure in the tube and being correspondingly sensitive whereby the increase in flow of air to the degree needed for propulsion is brought about in a minimum time interval and substantially instantaneously with 25 the insertion of a carrier in the tube while the discharge of the carrier likewise results in instantaneous restoration of flow conditions to normal, thus avoiding unduly prolonged air flow with consequent waste of 30 power.

In the drawings, in which two alternative forms of the invention are illustrated:—

Figure 1 is a vertical sectional view of a 35 pneumatic conveyer tube controlling device embodying the invention.

Figure 2 is a view similar to Figure 1 showing an alternative form of the invention.

Referring to the drawings one end of a 40 transmission tube is shown at 5, between which and an air moving means 6 which may be a header or drum connected to any suitable exhausting device, is a hollow housing or casing 7. It will be seen that a relatively 45 low pressure established in the drum 6 will produce a flow of air in the tube 5. This flow is regulated and controlled by a main valve 10 disposed within the housing or casing 7 and this controlling device forms 50 the subject matter of the present invention.

The main valve 10 is of balanced type having spaced apart heads 11 and 12 secured to a valve rod 15 and adapted to engage the 55 corresponding annular seats 13 and 14 defining orifice in the inner U-shaped wall 8

of the casing, said wall separating the chamber 22 which communicates with the transmission tube 5 from a chamber which communicates with the vacuum drum 6. The use of two separate valve members on the 60 same valve rod 15 produces a well-defined condition of balance, as will be clear, because of the oppositely acting and balancing pressures exerted on the separate members.

The valve rod 15 is mounted to slide longitudinally in bearing brackets 16 and 17 and normally the weight of the valve structure holds the valve members in engagement with their seats in the form of construction shown in Figure 1. The lower end of the valve rod 70 15 is attached to a diaphragm 18 which is exposed on its lower side to atmospheric pressure by way of the opening 19 in the casing 7, and which is exposed upon its upper side to the pressure condition at any 75 time existing within the chamber 22 and tube 5.

A by-pass or restricted opening 20 is provided in the wall 8 permitting a constantly effective slow leak from the chamber 22 to 80 the chamber 21 which communicates with the suction drum.

In operation assuming that no carrier is in the transit transmission tube 5, the pressure in the tube and chamber 22, is but 85 slightly lower than atmospheric pressure and the pressure conditions on opposite faces of the diaphragm 18 are thus so nearly equal that the weight of the diaphragm and valve parts is sufficient to prevent the diaphragm 90 from rising and unseating the valve heads. Only the minimum flow of air provided by the opening 21 is thus normally permitted to take place. Gravity may be aided in the valve seating operation by a differential 95 effect in the valve structure produced by forming the valve head 11 with a somewhat greater area than the area of the other valve head 12.

When a carrier is inserted at any sending 100 station into the transit tube 5 the pressure immediately drops in advance of the carrier and the light and substantially balanced main valve is practically instantly operated by the lifting action of the diaphragm 105 which is pressed upwardly by atmosphere acting on its lower face. This immediate opening of the valve is followed by a rush of air into the exhaust drum and results in 110 the propulsion of the carrier through the

- tube. The emergence of the carrier from the tube at an exit point is immediately followed by the snapping of the valve structure to closed position, this action apparently being assisted by a reaction or momentary surge of air through the tube and into the chamber 22 resulting in a momentary rise of pressure in the chamber above the pressure of the atmosphere.
- 10 In Figure 2 of the drawing there is shown a modified form of the invention in which a spring 25 is employed for moving the valves to their seats. By the use of the spring gravity is not made use of in the 15 operation of the valve and the structure can be placed in any position with relation to the horizontal.
- The closing of the valve to cut off the flow of air through the system is thus determined directly by the delivery of the 20 carrier from the transmission tube and is wholly independent of any timing device so that waste of power is substantially eliminated.
- 25 What I claim is:—
1. Power control apparatus for a pneumatic despatch system having a transmission tube comprising a casing having a chamber therein, a main valve controlling an orifice in a wall of the casing, a minimum flow of air from one side of said wall to the other normally being permitted, and a movable actuator connected to the valve, said actuator always being freely exposed upon one side to the atmosphere and at its other side to the pressure existing in said chamber, said actuator initiating opening of the main valve upon the occurrence of conditions in the transmission tube arising from the introduction of a carrier therein and immediately initiating closure of the main valve upon the occurrence of conditions in the transmission tube arising from discharge of the carrier from the latter.
- 45 2. Power control apparatus for a pneumatic despatch system having a transmission tube comprising a casing having a chamber therein, a normally closed valve controlling an orifice in a wall of said chamber, a minimum flow of air from one side to the other of the valve normally being permitted, and a movable actuator connected to the valve, said actuator being always freely exposed upon one side to atmospheric pressure and at its other to the pressure existing in said chamber, said actuator initiating opening of the main valve immediately upon introduction of a carrier into the transmission tube and closing of said valve immediately upon discharge of the carrier from the tube.
- 55 3. Power control apparatus for a pneumatic despatch system having a transmission tube, said apparatus comprising a casing connected to the transmission tube, said
- casing having a chamber therein, a main valve controlling an orifice in a wall of said chamber, a minimum flow of air from one side of said wall to the other normally being permitted, a diaphragm freely exposed at one side to atmospheric pressure and at its other side to the pressure in said chamber, and means connecting the diaphragm to the valve, the diaphragm being directly responsive to conditions arising in said chamber upon introduction of a carrier into the transmission tube and delivery of a carrier therefrom respectively to open the valve and to permit its closure immediately upon the occurrence of such respective conditions.
4. Power control apparatus for a pneumatic despatch system of the vacuum minimum-flow type having a transmission tube and exhaust means, said apparatus comprising a casing, a partition dividing the casing into an inlet chamber which always freely communicates with the transmission tube and an outlet chamber always in full communication with the exhaust means, said partition having a valve aperture therein, a balanced valve device governing the flow of carrier impelling air current from the inlet to the outlet chamber, a minimum flow of air from the inlet to the outlet chamber being permitted at all times, and a single element connected to the valve device for moving the latter, said element itself being directly responsive alternately to pressure and to the velocity effect of air flow in the inlet chamber to open the valve device and to permit it to close, said valve moving means being at all times exposed on one side to atmosphere pressure and at its other side to transmission tube pressure and opening the valve device upon introduction of a carrier into the tube and permitting it to close upon delivery of the carrier from the tube.
5. Power control apparatus for a pneumatic despatch system of the vacuum minimum-flow type having a transmission tube and exhaust means, said apparatus comprising a casing, a partition dividing the casing into an inlet chamber which always freely communicates with the transmission tube and an outlet chamber always in full communication with the exhaust means, said partition having a valve aperture therein, a movable valve member for closing said aperture, a minimum flow of air from the inlet chamber to the outlet chamber being permitted when the valve is in closed position, a pneumatic connected to the valve member, one side of the pneumatic being exposed at all times to the pressure in the inlet chamber and the other side of the pneumatic always being exposed to atmospheric pressure, the pneumatic responding directly to the reduction in pressure in the inlet chamber resulting from the reduction in the minimum flow due to intro-

duction of a carrier into the tube and by such response opening the valve to permit carrier impelling air flow through the valve aperture, the pneumatic also responding 5 directly to the sudden rush of air through the inlet chamber of the casing incident to delivery of the last carrier from the tube and by such response permitting the valve member to return to closed position thereby 10 to shut off the carrier impelling air flow.

6. Power control apparatus for a pneumatic despatch system of the vacuum minimum flow type having a transmission tube and an exhauster, said apparatus comprising 15 a casing having an inlet opening at one side and an outlet opening at the opposite side, the inlet communicating with the transmission tube and the outlet with the exhauster, a U-shaped partition within the 20 casing separating a chamber always communicating with the inlet from a chamber al-

ways communicating with the outlet, said partition having co-axial valve apertures in its parallel walls, a balanced valve having heads cooperating with the respective apertures, means providing for a minimum flow of air from the inlet to the outlet chamber at all times, a stem for the valve, guides for the stem, a diaphragm forming a movable side wall for the inlet chamber, the inner 25 surface of the diaphragm being exposed at all times to transmission tube pressure, the end of the stem projecting through the center of the diaphragm, and means connecting the diaphragm to the stem, the casing comprising 30 a dished cover plate protecting the outer side of the diaphragm, said plate having a central opening for the passage of the valve stem and to permit full access of atmospheric air to the outer face of the dia- 35 phragm.

JAMES G. MACLAREN.
